[57] CLAIM

The ornamental design for telephone set, as shown and described.

DESCRIPTION

FIG. 1 is a front, top and right side perspective view of a telephone set showing our new design;

FIG. 2 is a perspective view somewhat similar to FIG. 1 with (1) the handset inverted and spaced apart from the base; (2) the disc panel, removed from the base to show the dial keyboard, and spaced apart from it; and (3) the color panel detached from the stand and spaced to the right thereof;

FIGS. 3 and 4 are respectively front and rear elevational views of the telephone shown in FIG. 1;

FIGS. 5 and 6 are respectively top and bottom plan views thereof;

FIGS. 7 and 8 are respectively left and right side elevational views thereof.

FIG. 1

FIG. 2

FIG. 3

FIG. 4

FIG. 5

FIG. 6

FIG. 7

FIG. 8
